US00D353438S

United States Patent [19]

Yuksel

[11] Patent Number: Des. 353,438

[45] Date of Patent: ** Dec. 13, 1994

[54] MAGNETIC FUEL CONDITIONER

[75] Inventor: Levent Yuksel, Philadelphia, Pa.

[73] Assignee: North American Power Technologies, Philadelphia, Pa.

[**] Term: 14 Years

[21] Appl. No.: 937,655

[22] Filed: Aug. 26, 1992

[52] U.S. Cl. D23/207

CLAIM

The ornamental design for a magnetic fuel conditioner, as shown and described.

DESCRIPTION

FIG. 1 is a perspective view of a magnetic fuel conditioner according to my design;

FIG. 2 is a top plan view of the embodiment of FIG. 1; FIG. 3 is a left side elevation view thereof, the right side is a mirror image except for the attachment band;

FIG. 4 is a front elevation of the embodiment of FIG. 1; FIG. 5 is a rear elevation of the embodiment of FIG. 1; FIG. 6 is a bottom plan view of the embodiment of FIG. 1;

FIG. 7 is a perspective view of a second embodiment thereof;

FIG. 8 is a top plan view of the embodiment of FIG. 7; FIG. 9 is a left side elevation of the embodiment of FIG. 7 with the right side elevation being the mirrored image thereof;

FIG. 10 is a front elevation of the embodiment of FIG. 7 with the rear elevation being the mirrored image thereof; and,

FIG. 11 is a bottom plan view of the embodiment of FIG. 7.
